(57) **CLAIM**

The ornamental design for a graphical user interface for a display screen, as shown and described.

DESCRIPTION

This design application is related to U.S. patent application Ser. No. 11/903,773, filed Sep. 24, 2007, entitled “User-Defined Media Annotations on Dynamic Charts”, which is a continuation-in-part of U.S. patent application Ser. No. 11/732,863, filed Apr. 4, 2007, entitled “User-Defined Visual Indicators on Dynamic Charts”.

The single FIGURE illustrates a front view of the graphical user interface for a display screen.

The broken line showing a display screen is for illustrative purposes only, and forms no part of the claimed design. The portions of the graphical user interface for a display screen shown in broken lines are for illustrative purposes only, and form no part of the claimed design.
